SPEED SENSITIVE GOVERNOR

John W. Marsh, United States Army,
Washington, D. C.Continuation of application Serial No. 324,002,
March 14, 1940. This application September
25, 1942, Serial No. 459,615

4 Claims. (Cl. 74—192)

(Granted under the act of March 3, 1883, as
amended April 30, 1928; 370 O. G. 757)

The invention described herein may be manufactured and used by or for the Government for governmental purposes, without payment to me of any royalty thereon.

This application is a continuation of my pending application entitled "Speed sensitive governor," filed March 14, 1940, Serial No. 324,002, and the invention forming the subject-matter thereof relates to speed sensitive governors for internal combustion engines and the like.

Heretofore mechanical governors have been capable of limiting engine speed to a predetermined maximum and have been effective only at the engine speed which is required to rotate the governor weights at a speed developing sufficient centrifugal force to overcome the resistance of the engine throttle. It is desirable to provide control of engine speed over the entire speed range of the engine. Such control will permit application of load to the engine without manual manipulation of the throttle, without stalling the engine when load is applied and without the necessity for operating the engine as the load is applied, at a speed deleterious to the clutching mechanism. Such control will also provide uniform engine speed, under the control of the operator, regardless of variations in load.

The primary object of the present invention is to devise a practical and effective governor which will regulate the speed of a throttle controlled engine to any desired speed regardless of the load, within the capacity of the engine.

Another object of this invention is to provide a governor acting directly on the engine throttle so that the operation of secondary mechanism, dependent upon throttle operation, is not disturbed and operates as intended.

It is a further object of this invention to provide a device to actuate any secondary mechanism at any operatively determined rotative speed of the primary mechanism.

Other objects of this invention are to provide a governor assembly wherein the drive between the driving and driven shafts is normally disrupted but automatically established under operating conditions of the engine with which the governor is associated, thus eliminating load conditions within the governor assembly during idle periods of the engine; to provide a governor assembly affording a positive control for each of the axially movable friction wheels on the driving and driven shafts; and to provide a governor mechanism in which the controlled fluid also supplies the requisite lubrication for the rotary components of the assembly within its casing.

The foregoing and other important objects of the present invention are accomplished by operating the governor mechanism through a controllable variable speed ratio changing mechanism, and will be apparent from the following description in conjunction with the accompanying drawing, and in the appended claims.

In the accompanying drawing, wherein like characters are employed to designate corresponding parts, Figure 1 is a longitudinal, partially sectional view, through a form of governing device accomplishing the objects of this invention. This figure illustrates the two elements required, to wit: A, a variable speed ratio changing mechanism, and B, a centrifugal governing mechanism. Figure 2 is a transverse partially sectional view through line 2—2 on Figure 1. This figure illustrates the structure of the manual control mechanism of the variable speed ratio changing mechanism A. Figure 3 is a transverse sectional view through line 3—3 of Figure 1, and illustrates the infinitely variable speed ratio changing device of mechanism A.

These mechanisms are, in the form shown, contained in a common housing 1. Shaft 2 is intended to be driven by the engine to be governed, at a speed proportionate to the engine speed. A pair of cones, 4 and 5, are slidably mounted on the splined portion 3 of shaft 2. Cone 4 is journaled in extension 6 of cover 7, secured to housing 1, this mounting being such as to resist axial movement of cone 4 towards cover 7. Cone 5 is journaled in piston 8, the mounting being such that cone 5 and piston 8 coact axially. Piston 8 is slidably mounted in cavity 9 of housing 1, and in axial alignment with extension 6 and shaft 2. Conduit 10 is intended to connect cavity 9 with a pressure lubricating system such as that of the engine, so that lubricating fluid pressure is maintained in cavity 9 and against piston 8, urging piston 8 and cone 5 towards cone 4.

Shaft 11 is positioned parallel to shaft 2, journaled in housing 1 at 12 and provided with splines 13. A pair of cones, 14 and 15, are slidably mounted on the splined portion 13 of shaft 11. Cone 15 is journaled in housing 1, this mounting being such as to resist axial movement of cone 15 towards the governing mechanism B. Cone 14 is journaled in piston 16, the mounting being such that cone 14 and piston 16 coact axially. Piston 16 is slidably mounted in cavity 17 in housing 1, and in axial alignment with shaft 11.

Shaft 18 is suitably mounted in housing 1, transversely to shafts 2 and 11, and having arm 19 secured thereto within cavity 17, positioned

to engage surface 20 of piston 16. Manual operating lever 21 is secured to shaft 18 external to housing 1, and coacts with shaft 18 and arm 19 to urge piston 16 and cone 14 towards cone 15.

Ring 22 is mounted between cones 4, 14 and 5, 15. An opening 23 is provided in housing 1 for the insertion of ring 22, and closed by cover 24 secured to housing 1.

The operation of the speed changing mechanism A is as follows:

Pressure of lubricating fluid in cavity 9, against piston 8, urges cone 5 axially towards cone 4, and by the wedging action of the opposed cones, produces contact between the inner edges of the ring 22 and the conical surfaces of cones 4 and 5. Fluid pressure on piston 8 continues to urge cone 5 axially towards cone 4, and ring 22 to the outer peripheries of cones 4 and 5 and to the inner peripheries of cones 14 and 15, thus urging cone 14 axially away from cone 15, until the limit of axial travel of cone 14 and piston 16, as determined by the position of arm 19, is reached, and gripping contact is produced between the inner edges of ring 22 and the conical surfaces of cones 14 and 15 and between the conical surfaces of cones 4 and 5. Rotation of shaft 2 is transmitted through splines 3 to cones 4 and 5, thence, by gripping contact between cones 4 and 5 and the inner edges of ring 22, to ring 22, thence, by gripping contact between the inner edges of ring 22 and cones 14 and 15, and splines 13, to shaft 11. The rotative speed of shaft 11 relative to shaft 2 is determined by the position of the ring 22 on the conical surfaces of cones 4, 5 and 14, 15, which position is determined by the axial positioning of cones 4, 5 and 14, 15. This axial positioning is determined by the position of arm 19, which limits the axial movement of piston 16 and cone 14 journaled therein.

When manual operating lever 21 and arm 19 are moved away from the governor mechanism B, the contact edges of ring 22 assume a position towards the inner peripheries of cones 14 and 15 and towards the outer peripheries of cones 4 and 5, and shaft 11 is rotated at a speed relatively greater than that of shaft 2. When manual operating lever 21 and arm 19 are moved towards governor mechanism B, the contact edges of ring 22 assume a position towards the outer peripheries of cones 14 and 15 and towards the inner peripheries of cones 4 and 5, and shaft 11 is rotated at a speed relatively less than that of shaft 2. Thus it will be seen that any rotative speed ratio between shafts 2 and 11, within the limits of the mechanism, can be obtained by the manual operation of lever 21 and the resultant position of arm 19.

In the centrifugal governor mechanism B, a plurality of arms 25, 26, is secured to shaft 11 and provided with pins 27, 28. Weights 29, 30 are pivotally mounted on pins 27, 28, and positioned relative thereto so that the rotation of weights 29, 30 about shaft 11 causes centrifugal angular movement of weights 29, 30 about pins 27, 28.

Collar 31 is slidably mounted on extension 32 of shaft 11, and journaled within collar 33 of plunger 34 so as to coact axially with plunger 34. Plunger 34 is slidably mounted within extension 35 of cover 36, which is secured to housing 1. Spring 37 is mounted between collar 33 and cover 36 urging plunger 34 and collar 31 towards the speed changing mechanism A. Arms 38, 39 are secured to weights 29, 30, and positioned to engage collar 31, so that the centrifugal movement

of weights 29, 30, through arms 38, 39, urges collar 31 and plunger 34 away from the speed change mechanism A against the pressure of spring 37.

An engine throttle mechanism is indicated at 5 C, connected to plunger 34, through connecting link 40, pivotally secured to plunger 34 at pin 41.

Lubrication of the device is effected by escape of lubricating fluid past piston 8 into the speed ratio changing mechanism A, and by the escape of lubricating fluid through orifice 42 into the governor mechanism B. Drainage of lubricating fluid is effected through conduit 43.

The operation of governor mechanism B is as follows:

Shaft 11, arms 25, 26 and weights 29, 30 being rotating, the position of weights 29, 30 and arms 38, 39 is determined by the combination of centrifugal force in weights 29, 30 and the pressure of spring 37 against collar 33. Any increase in speed of shaft 11 produces a centrifugal movement of weights 29, 30 and consequent axial movement of collar 31 and plunger 34 away from the speed changing mechanism A, overcoming the pressure of spring 37 and acting through link 40, urges the throttle mechanism C towards closed position. Any decrease in speed of shaft 11 permits a centripetal movement of weights 29, 30, and plunger 34 is urged by spring 37 towards the speed changing mechanism A, and acting through link 40 urges the throttle mechanism C towards open position.

The combination of the speed changing mechanism A and the engine governor mechanism B, in the manner disclosed, provides governed regulation of any engine speed within the limits of the engine and mechanism at the will of the operator. Movement of manual control lever 21 away from governor mechanism B, produces a high governor speed relative to engine speed, so that the governor is effective at low engine speed. Movement of manual control lever 21 towards governor mechanism B produces a low governor speed relative to engine speed, so that the governor is effective at high engine speed. Any intermediate positioning of manual control lever 21 produces a governor speed to control and maintain engine speed according to the manual setting.

It is apparent that the combination of mechanisms disclosed may be applied to all forms of engine and other devices wherein it is desired to operatively regulate speed, or where it is desired to effect the operation of an associated device by the speed of the driving element at any operatively selected speed of the driving element. This invention may be embodied in other forms, with other speed ratio changing mechanisms and with other governing mechanisms, without departing from the spirit or essential characteristics thereof. The present embodiment is therefore to be considered in all respects as illustrative and not restrictive, the scope of the invention being indicated by the appended claims rather than by the foregoing description, and all changes that come within the means and range of equivalency of the claims are therefore intended to be embraced therein.

Having described my invention, what I claim as new and wish to secure by Letters Patent is:

1. A speed ratio changing device comprising driving and driven shafts, a pair of opposed friction wheels mounted on each of said shafts and rotatable therewith, one wheel of each pair being movable axially of its shaft, the remaining wheel of each pair being restrained against such move-

ment, means coacting with said friction wheels for establishing a normally inoperative driving connection between their respective shafts, said means being both mechanically and hydraulically operable to drive said shafts at selected speed ratios and including a power transmitting ring encircling the shafts and extending between opposed friction wheels, mechanically controlled camming means coacting with the axially movable wheel on said driven shaft, said camming means being adjustable for positioning said wheel at different points lengthwise of its shaft to determine the speed of the driven relative to said driving shaft, and hydraulically controlled means connected with the axially movable wheel on said driving shaft and adapted to be actuated by a control fluid, said means in response to a predetermined pressure normally prevailing in the control fluid serving to urge the axially movable wheel on the driving shaft toward the opposite wheel thereon with sufficient pressure to establish a driving connection between said driving and driven shafts at a speed ratio determined by the adjustment of said camming means.

2. A speed ratio changing device comprising a casing, driving and driven shafts rotatably journaled within the casing, a pair of opposed friction wheels mounted on and splined to each of said shafts, one wheel of each pair being movable axially of its shaft, the remaining wheel of each pair being restrained against such movement, means coacting with said wheels for establishing a normally inoperative driving connection between their respective shafts, said means being mechanically and hydraulically operable to drive said shafts at selected speed ratios and including a power transmitting ring encircling the shafts and extending between their opposed wheels, mechanically controlled camming means pivotally mounted within the casing and cooperating with the axially movable wheel on said driven shaft, said means being manually adjustable from a point exterior of the casing for positioning said wheel at different points lengthwise of its shaft to determine the speed of said driven relative to said driving shaft, and hydraulically operated means rotatably journaling the axially movable wheel on said driving shaft and adapted to be actuated by a control fluid, said means in response to a predetermined pressure normally prevailing in the control fluid serving to urge the axially movable wheel on the driving shaft toward the opposite wheel thereon with sufficient pressure to establish a driving connection between said driving and driven shafts at a speed ratio determined by the adjustment of said camming means.

3. A speed ratio changing device comprising a casing, driving and driven shafts rotatably journaled within the casing, a pair of opposed friction wheels mounted on and splined to each of said shafts, one wheel of each pair being movable axially of its shaft, the remaining wheel of each pair being restrained against such movement, means coacting with said wheels for establishing a nor-

mally inoperative driving connection between their respective shafts, said means being mechanically and hydraulically operable to drive said shafts at selected speed ratios and including a power transmitting ring encircling the shafts and extending between their opposed wheels, mechanically controlled camming means pivotally mounted within the casing and cooperating with the axially movable wheel on said driven shaft, said means being manually adjustable from a point exterior of the casing for positioning said wheel at different points lengthwise of its shaft to determine the speed of said driven relative to said driving shaft, a hydraulically controlled piston slidably mounted within the casing and adapted to be actuated by a control fluid, said piston rotatably journaling the axially movable wheel on said driving shaft, whereby said piston in response to a predetermined pressure normally prevailing in the control fluid will urge said axially movable wheel on the driving shaft toward its opposed wheel with sufficient pressure to establish a driving connection between said driving and driven shafts at speed ratios determined by the adjustment of said camming means.

4. A speed ratio changing device comprising a casing, driving and driven shafts rotatably journaled within the casing, a pair of friction wheels mounted on and splined to each of said shafts, one wheel of each pair being movable axially of its shaft, the remaining wheel of each pair being restrained against such movement, means coacting with said wheels for establishing a normally inoperative driving connection between their respective shafts, said means being mechanically and hydraulically operable to drive said shafts at a selected speed ratio and including a power transmitting ring encircling the shafts and extending between the opposed wheels thereon, a lower cylinder within said casing, a mechanically controlled piston mounted for sliding movement within said cylinder and connected with the axially movable wheel on said driven shaft, camming means pivotally mounted within the casing and coacting with said piston for positioning the axially movable wheel on said driven shaft at different points lengthwise of said shaft to determine the speed of the driven relative to the driving shaft, said means being manually adjustable from a point exterior of the casing, an upper cylinder within said casing, a hydraulically controlled piston slideable within said cylinder and adapted to be actuated by a control fluid, said piston rotatably journaling the axially movable wheel on the driving shaft whereby said piston in response to a predetermined pressure normally prevailing in the control fluid will urge said axially movable wheel on the driven shaft toward its opposed wheel with sufficient pressure to establish a driving connection between said driving and driven shafts at speed ratios determined by adjustment of said camming means.

JOHN W. MARSH.
